UNITED STATES PATENT OFFICE

HANS JOHANNSEN, OF SANGERHAUSEN, GERMANY

AUTOMATIC TARGET

Application filed May 23, 1931, Serial No. 539,615, and in Germany May 30, 1930.

This invention relates to a target of the kind composed of a plurality of concentric rings connected to indicating plates and adapted to deflect the latter automatically under the impact of the bullets for indicating the nature of the hit.

One object of the invention is to facilitate the movement of the rings, and the invention consists in this respect in the provision of spherical ring supports about which the rings can oscillate, the supports being concentric with the rings.

Another object of the invention is to provide improved means for imparting movement from the rings to the indicating plates, and in this respect the invention consists in the provision of horizontal rods which co-operate with thrust members for deflecting the plates in their own planes.

Means are provided for retaining the rings in operative position and for restoring one ring automatically to its position of rest on another ring being operated.

Fig. 1 of the accompanying drawings represents a diagrammatic front view of the target structure and part of the mechanism,

Fig. 2 is a sectional side view showing part of the mechanism,

Fig. 3 is a part view on an enlarged scale,

Fig. 4 is another part view of the mechanism,

Fig. 5 is a sectional view showing a modified form of part of the mechanism,

Fig. 6 is a view showing a modification of another part of the mechanism; and

Fig. 7 is a sectional view at right angles to Fig. 6.

The target comprises a plurality of coaxial rings 4 of different diameters arranged one behind another in order of size. The ring supports consist of spherical collars 2 which are threaded together with spacing members 3 on a horizontal tube 6b. If desired, collars and spacing members may be integral with the tube. The target support comprises vertical, parallel plates 1, 8 and 8a connected by suitable stay rods. The front plate 1 carries the tube 6b. The target rings are mounted on the collars 2 by means of bearings 4a situated in the geometrical centre as well as

in the centre of gravity of the rings, and the latter will therefore be oscillated by impact with a bullet irrespective of the position in which they are hit. The rings are normally maintained in a vertical position by horizontal rods 14 which are arranged to slide in the plates 1 and 8 and which bear against the rings under the influence of springs 24. There are four symmetrically distributed control rods for each ring, and each rod cooperates with an indicating plate 10 for indicating that it has been hit and where. The plates 10 are pivotally arranged on shafts 9 at the four corners of the square supporting frame and are deflected in their own planes. Each plate is balanced by an arm 21 carrying a weight 11 and tends to remain in a concealed position within the supporting frame. The deflection of the plates may be effected, as shown in Fig. 3, either by means of thrust members 12 connected to the rods and provided with inclined surfaces which bear against the edges of the plates, or by means of bell cranks 26. The rearmost indicating plates are preferably operated by means of angular thrust plates 25 secured to the ends of the respective rods 14. In either case the movement of a rod, caused by the impact of a bullet with the respective portion of a ring, is transmitted to the respective plate so as to swing the latter into a laterally projecting position. Pivoted catches 19 may be provided for engaging the deflected arms 21 and retaining the indicating plates in operative position. The catches are double-armed and controlled by a centrally mounted, spring-pressed, universal bar 16, the latter being provided with notches 20 in which the tail ends of all the catch levers engage. Each rod 14 carries an arm 15 which co-operates with a pin 18 on the bar 16 for operating the latter. Thus the bar will be moved and all the catches deflected each time a ring is hit, and a previously engaged indicating plate 10 will therefore be released before the next plate reaches its catch and is engaged thereby. The release plate returns to its position of rest and is aided in this movement by a spring 22 (Fig. 1).

Fig. 6 shows a modified arrangement

wherein the weighted arms of the plates 10a are adapted, on being deflected, to snap behind shoulders 12a on leaf-springs 13a for retaining the plates in operative position. 5 All the springs are connected to a rope 10 which is controlled by a spring 14a and which can be operated from the shooting stand for releasing the plates.

Where the shooting distance is small and 10 allows the target to be easily seen, the retaining device may be unnecessary, the plates being merely balanced so as to return slowly to the rest position.

The bull's eye consists of a disc or block 6 15 provided with a bore 6a whereby it is arranged to slide on the outer end of the tube 6b. It is connected to a rod 5 which is arranged to slide inside the tube and controlled by a spring.

20 The indicating plate 7 for the bull's eye may, as shown in Fig. 1, be connected to one arm of a bell crank which bears against the end of the rod 5 and which is deflected by the latter for turning the plate from a horizontal into an upright position.

25 A modified arrangement is shown in Fig. 5 where the bull's eye co-operates with a vertical indicating plate 30 which is supported by a plunger 29 arranged together with a piston 32 to move up and down in a dashpot 31. The plunger rests on a bell crank 27 which is pivoted at 28 and which bears against the end of the rod 5. On the bull's eye being hit, the impact is transmitted by 35 the bell crank to the plunger which then makes a rapid ascending movement. The air in the dashpot forms a cushion for the piston 32 and ensures a slow return movement of the plunger and of the indicating plate. The 40 outlet 33 through which the air escapes from the dashpot can be adjusted by means of a shutter 34 for regulating the descending movement of the plate.

The rods 14 may be carried through and 45 guided in the plate 8a, and the springs 24 may be arranged on the outer ends of the rod and protected by a casing 9a, as shown by dotted lines in Fig. 2. In this case the plate 8 may be omitted.

50 Since there are four indicating plates for each ring it is evident that indications will be obtained not only as regards the hitting of any particular ring but also as regards the ring portion which receives the bullet.

55 I claim:

1. An automatic target comprising a plurality of co-axial target rings, spherical supports for said rings allowing the latter to be oscillated about their centres, indicating 60 means, and connection between the rings and said indicating means for operating the latter.

2. A target as claimed in claim 1 wherein the supports consist of spherical collars, and 65 a rod whereon said collars are threaded.

3. An automatic target comprising a plurality of co-axial target rings, spherical supports for said rings allowing the latter to oscillate about their centres on impact with the bullets, pivoted indicating plates movable in their own planes, and connections between the rings and said plates for transmitting deflecting movement to the latter. 70

4. A structure as claimed in claim 3 wherein in the connections between the rings and the plates comprise slidable rods arranged with one end in contact with the rings, thrust members connected to said rods and formed with inclined surfaces arranged to strike 80 against and deflect the indicating plates on the rods being moved, means for retaining the plates in deflected position, and means for restoring them to their normal positions.

5. An automatic target comprising a horizontal tube, a plurality of spherical spaced 85 collars on said tube, target rings of different diameters mounted on said collars, each ring being concentric with its supporting collar and capable of oscillating about it under impact with the bullets, horizontal, slidable, 90 spring-controlled rods arranged behind the rings and adapted to receive motion therefrom, indicating plates adapted to be deflected in their own planes and tending to remain in a given position, thrust members adapted 95 to transmit motion from the rods to the plates for deflecting the latter, catches adapted to retain the plates in deflected position, a universal, spring-controlled bar controlling said catches, and connections between the rods and the universal bar for moving the latter and releasing one plate before another is thrown into engagement with its catch. 100

6. A structure as claimed in claim 5 wherein in the thrust members consist of bell crank levers. 105

7. The structure claimed in claim 5 in combination with a disc forming the bull's eye, a rod carrying said disc and arranged to slide in the horizontal tube, a 110 vertically movable indicating plate, a bell crank supporting said latter indicating plate and co-operating with the rod carrying the bull's eye disc for raising the plate on the disc being hit by a bullet, and a dashpot for 115 retarding the descending movement of the plate. 120
